UNITED STATES PATENT OFFICE

GEORGE F. HICKOK, OF SAN FRANCISCO, CALIFORNIA

CHOKER HOOK FOR LOGGING

Application filed February 18, 1929. Serial No. 340,730.

My invention relates to improvements in choker hooks for logging operations and the like wherein a ferrule secured upon the end of a choker cable is engaged and held within a recess formed in the body of the hook by means of a latch slidably movable to release the ferrule when the cable is taut.

The primary object of my invention is to provide an improved choker hook.

Another object is to provide an improved choker hook which will facilitate the securing and releasing of a choker cable upon logs and the like.

A further object is to provide an improved device of the character described which may be operated to release the choker ferrule when the cable is taut and without requiring any slackening of said cable.

Another object is to provide an improved choker hook of improved construction reducing the bulk and weight of the hook without reducing the strength and ruggedness thereof.

A further object is to provide an improved device having improved latching means operating to efficiently secure the ferrule of a choker cable and facilitating the release of said ferrule when desired.

A further object is to provide an improved latching means for choker hooks which is simple and efficient in operation and which will prevent dirt or other foreign material from impairing the operation of the latch.

A still further object is to provide an improved device of the character described which can be manufactured economically and which is durable and efficient in operation.

I accomplish these and other objects by means of the improved device disclosed in the drawings forming a part of the present application wherein like characters of reference are used to designate similar parts throughout the specification and drawings, and in which—

Fig. 1 is a front elevation of my improved choker hook;

Fig. 2 is a side elevation;

Fig. 3 is a bottom view of the hook as shown in Fig. 1;

Fig. 4 is a vertical mid-sectional view of the hook;

Fig. 5 is a vertical mid-sectional view taken at right angles to the position shown in Fig. 4; and

Fig. 6 is a horizontal sectional view taken upon the line 6—6 of Fig. 4 in the direction indicated with the latch in open position.

Referring to the drawings, the numeral 1 is used to designate the body of a choker hook, said body being provided with the usual slip-sleeve 2 formed upon one end and adapted to receive a choker cable reeved therethrough. A recess 3 is formed in the opposite end of the body 1, said recess being cylindrical in form and being adapted to receive a ferrule 4 of the ordinary type secured upon a choker cable 6, said ferrule being inserted into said recess 3 through an opening 7 in the end of the body 1 opposite the slip-sleeve.

A latch plate 8 is slidably mounted within a latch recess 9 formed in the body 1 in slightly spaced relation to the open end thereof, said recess being cut to form guide grooves 9' within opposite sides of the body. The latch plate 8 is made slightly wedge shaped, the lower surface being inclined slightly with respect to the plane of the upper surface whereby the plate is tapered toward the inner end. The lower supporting surface of the guide grooves 9' are inclined slightly to correspond to the incline of the lower plate surface. The latch plate 8 is slidably movable into the recess 9 through one side of the body 1, and the inner end of the plate is slotted as at 11 to span the choker cable 6 whereby the cable may pass the latch while the ferrule 4 is seated upon the latch plate as indicated in Figs. 4 and 5 of the drawings.

A longitudinal recess 12 is formed within one side of the latch plate 8, said recess opening outwardly through the outer end of the plate 8. A bearing bore 13 is formed in the inner end of the plate co-axial with the recess 12 and communicating therewith. A guide rod 14 is secured upon the body and arranged to extend into the recess 12 through the bearing bore 13. A compression spring 16 is mounted within the recess 12 upon the rod 14, said spring seating against the inner end of

the recess, and being engaged by a nut 17 threaded onto the end of the rod 14. The rod 14 is preferably carried by a plug 18 tapped into the outer end of a bore 19 formed in the body co-axial with the bore 13 and recess 12 of the plate 8, and the outer end of the recess 12 is closed by a suitable plug 21 tapped thereinto to prevent the entrance of dirt or other foreign matter into the recess whereby the normal operation of the spring 16 might be impaired.

The inner ends of the portions of the latch plate at the sides of the slot 11 are inwardly inclined as at 22 whereby dirt or other foreign matter accumulating in the guide grooves 9' will be displaced inwardly to the recess 3 when the plate 8 is moved inwardly to its normal position.

A shoulder 23 is formed by a notch 24 cut upon the upper surface of the latch plate 8 adjacent its outer end, said notch and shoulder being arranged to be engaged by a suitable prying tool 26 inserted into engagement therewith through a notch 27 formed in the body 1 immediately over the open end of the latch recess 9 and opposite the notch 24 of the plate 8. An outwardly extending lip 28 is formed immediately over the notch 24 to act as a fulcrum against which the prying tool 26 may be turned, said lip also serving to deflect dirt or foreign matter away from the notch.

In operation, the cable 6 is reeved through the slip-sleeve 2 in the ordinary manner. The ferruled end of the cable is passed around a log or the like, and the ferrule 4 inserted through the opening at the outer end of the recess 3, the latch plate 8 being moved outwardly against the pressure of the spring 16 to a releasing position as shown in full lines in Fig. 6 of the drawings. As the ferrule 4 passes the plate 8, said plate is released and is moved to securing position by the pressure of the spring 16 compressed between the back of the plate recess 12 and the nut 17 of the rod 14. As the latch plate 8 moves inwardly, the slot 11 moves over the cable 6 and the side portions of the plate form a seat for the ferrule whereby said ferrule is secured within the recess. As the cable 6 is drawn taut, the ferrule 4 is held firmly seated upon the plate 8 and the pressure upon the plate is added to the pressure of the spring 16 as a means for effectually holding the latch plate in latching position.

To release the ferrule 4, a prying tool 26 such as a crow-bar or other suitable instrument, is inserted through the notch 27 into engagement with the notch 24 and shoulder 23, and by turning said tool against the lip 28 as a fulcrum, the latch plate 8 is moved outwardly from its normal position as indicated in dotted lines in Fig. 6 of the drawings, to the releasing position indicated in full lines. This may be accomplished without requir-

ing any slackening of the cable 6 and while said cable is taut. The inclined bearing surfaces between the lower face of the plate 8 and the grooves 9' causes the pressure upon said plate 8 to be relieved by the first slight movement of said plate outwardly, the further movement of said plate being thus facilitated. This is an important feature of my invention, as in hooks of the types commonly known and used heretofore, a substantial slackening of the cable 6 is necessary before the ferrule may be released, and, as the cable is often held taut by the pressure of the log thereon, the releasing is frequently rendered very difficult.

My improved construction above described permits the ferrule to be engaged and disengaged with a minimum of slack, and requires a minimum of clearance for the ferrule when inserted into operative engagement, thereby reducing the length of the hook necessary to accommodate the ferrule and hence reducing the size and weight of the body. The device is free from outward obstructions which might catch upon external objects and interfere with the movement of the hook and log.

While I have illustrated and described what I regard as the preferred embodiment of my invention, the specific details of construction may of course be modified without departing from the spirit of my invention. I therefore do not wish to restrict myself to the details illustrated and described, but desire to avail myself of all modifications which may fall within the scope of the appended claims.

Having thus described my invention what I claim as new and desire to secure by Letters Patent is:

1. A choker hook comprising a body provided with a slip-sleeve formed upon one end and having an axial recess and opening within the opposite end to receive a choker cable ferrule; and a latch slidably mounted within the body adjacent the opening and adapted to form a seat for the ferrule to detachably secure said ferrule within the recess.

2. A choker hook comprising a body provided with a slip-sleeve formed upon one end and having an axial recess and opening within the opposite end to receive a choker cable ferrule; a latch slidably mounted within the body adjacent the opening and adapted to form a seat for the ferrule to detachably secure said ferrule within the recess; and means for normally moving the latch to a closed position.

3. A choker hook comprising a body provided with a slip-sleeve formed upon one end and having an axial recess and opening within the opposite end to receive a choker cable ferrule; a latch slidably mounted within the body adjacent the opening and adapted to form a seat for the ferrule to detachably secure said ferrule within the recess; and a

spring mounted in connection with the latch and normally moving said latch to a closed position.

4. A choker hook comprising a body provided with a slip-sleeve formed upon one end and having an axial recess and opening formed within the opposite end to receive a choker cable ferrule; a latch slidably mounted within the body adjacent the opening and adapted to form a seat for the ferrule to detachably secure said ferrule within the recess; a guide rod secured upon the body and extending into slidable engagement with the latch; and a compression spring mounted within the latch and engaging the rod to normally move the latch to a closed position.

5. A choker hook comprising a body provided with a slip-sleeve formed upon one end and having an axial recess and opening formed within the opposite end to receive a choker cable ferrule; a latch slidably mounted in guides formed within the body adjacent the opening, said latch being slotted to receive the choker cable and being movable outwardly from one side of the body to uncover the opening; and a spring mounted in connection with the latch for normally moving said latch to a closed position.

6. A choker hook comprising a body provided with a slip-sleeve formed upon one end and having an axial recess and opening formed within the opposite end to receive a choker cable ferrule; a latch slidably mounted in guides formed within the body adjacent the opening, said latch being slotted to receive the choker cable and being movable outwardly from one side of the body to uncover the opening; a guide rod secured to the body and extending into a recess formed in the latch; and a spring mounted upon said rod within the recess of the latch to normally move said latch to a closed position extending across the opening.

7. A choker hook comprising a body provided with a slip-sleeve formed upon one end and having an axial recess and opening formed within the opposite end to receive a choker cable ferrule; a latch slidably mounted in guides formed within the body adjacent the opening, said latch being slotted to receive the choker cable and being movable outwardly from one side of the body to uncover the opening; a guide rod secured to the body and extending into a recess formed in the latch; a spring mounted upon said rod within the recess of the latch to normally move said latch to a closed position extending across the opening; and means adapted to receive a tool for moving the latch to releasing position when the cable is taut.

8. A choker hook comprising a body provided with a slip-sleeve formed upon one end and having an axial recess and opening formed within the opposite end to receive a choker cable ferrule; a latch slidably

mounted in guides formed within the body adjacent the opening, said latch being slotted to receive the choker cable and being movable outwardly from one side of the body to uncover the opening; a guide rod secured to the body and extending into a recess formed in the latch; and a spring mounted upon said rod within the recess of the latch to normally move said latch to a closed position extending across the opening; and a shoulder formed upon the latch adjacent the outer end thereof, and accessible through a notch formed in the body adjacent thereto, said shoulder being adapted to be engaged by a tool for moving the latch to releasing position when the cable is taut.

9. A choker hook comprising a body provided with a slip-sleeve formed upon one end and having an axial recess and opening formed within the opposite end to receive a choker cable ferrule; a latch slidably mounted in guides formed within the body adjacent the opening, said latch being slotted to receive the choker cable and being movable outwardly from one side of the body to uncover the opening; a guide rod secured to the body and extending into a recess formed in the latch; a spring mounted upon said rod within the recess of the latch to normally move said latch to a closed position extending across the opening; a shoulder formed upon the latch adjacent the outer end thereof, and accessible through a notch formed in the body adjacent thereto, said shoulder being adapted to be engaged by a tool for moving the latch to releasing position when the cable is taut; and a lip formed upon the body adjacent the shoulder to form a fulcrum for said tool.

10. A choker hook comprising a body having an opening and recess formed in one end thereof to receive a ferrule secured upon the end of a choker cable and movable axially into the opening and recess; and means for detachably securing the ferrule in a normal seated position within the recess, said means being movable to release the ferrule and permit the same to be moved axially outward from the recess while the cable is taut and without moving the ferrule inwardly from its normal seated position within the recess.

11. A choker hook comprising a body having an opening and recess formed in one end thereof to receive a ferrule secured upon the end of a choker cable and movable axially into the opening and recess; means for detachably securing the ferrule in a normal seated position within the recess, said means being movable to release the ferrule and permit the same to be moved axially outward from the recess while the cable is taut and without moving the ferrule inwardly from its normal seated position within the recess; and means for normally holding the securing means in ferrule securing position.

12. A choker hook comprising a body hav-

ing an opening and recess formed in one end thereof to receive a ferrule secured upon the end of a choker cable and movable axially into the opening and recess; a latch plate slidably mounted within the body adjacent the opening to detachably engage and secure the ferrule within the recess, said latch forming a seat for the ferrule and being movable to release the ferrule and permit axial outward movement thereof while the cable is taut.

13. A choker hook comprising a body having an opening and recess formed in one end thereof to receive a ferrule secured upon the end of a choker cable and movable axially into the opening and recess; a latch slidably mounted within the body adjacent the opening to detachably engage and secure the ferrule within the recess, said latch forming a seat for the ferrule and being laterally movable outwardly from the side of the body to release the ferrule and permit axial outward movement thereof while the cable is taut.

14. A choker hook comprising a body having an opening and recess formed in one end thereof to receive a ferrule secured upon the end of a choker cable; a latch plate slidably mounted within the body adjacent the opening to detachably engage and secure the ferrule within the recess, said plate being tapered and supported upon an inclined surface and being movable to release the ferrule while the cable is taut.

15. A choker hook comprising a body having an opening and recess formed in one end thereof to receive a ferrule secured upon the end of a choker cable; a latch plate slidably mounted within guides formed within the body adjacent the recess opening to detachably engage and secure the ferrule within the recess, said plate being of tapered thickness toward its inner end and supported upon an inclined surface corresponding to the taper of the plate; and means for normally holding the latch plate in ferrule securing position.

16. A choker hook comprising a body having an opening and recess formed in one end thereof to receive a ferrule secured upon the end of a choker cable; a latch plate slidably mounted within the body adjacent the recess opening to detachably engage and secure the ferrule within said recess, the outer end of said plate normally being flush with the side of the body and being outwardly movable from said side to release the ferrule; and means for normally moving the latch to ferrule securing position.

17. A choker hook comprising a body having an opening and recess formed in one end thereof to receive a ferrule secured upon the end of a choker cable; a latch plate slidably mounted within the body adjacent the recess opening to detachably engage and secure the ferrule within said recess, the outer end of said plate normally being flush with the side of the body and being outwardly movable

from said side to release the ferrule, said latch plate having a longitudinal recess formed in one side thereof and a bearing aperture formed in the inner end of the plate and communicating with said longitudinal recess; a guide rod secured to the body and extending into the latch recess through the bearing aperture; and a spring mounted within the latch recess in connection with the rod to normally move the latch to ferrule securing position and to limit the outward movement of said latch.

18. A choker hook comprising a body having an opening and recess formed in one end thereof to receive a ferrule secured upon the end of a choker cable; a latch plate slidably mounted within guide grooves formed in the body adjacent the recess opening to detachably engage and secure the ferrule within the body, said plate being laterally movable to release the ferrule and provided with inclined inner ends adapted to displace foreign matter from the guide grooves.

19. A choker hook comprising a body having an opening and recess formed in one end thereof to receive a ferrule secured upon the end of a choker cable; a latch plate slidably mounted within guide grooves formed in the body adjacent the recess opening to detachably engage and secure the ferrule within the body, said plate being movable outwardly from the side of the body to release the ferrule; means for normally moving the latch plate to ferrule securing position; and a shoulder formed adjacent the outer end of the plate and accessible through a notch formed in the body adjacent thereto for moving the plate outwardly to release the ferrule when the cable is taut.

20. A choker hook comprising a body having an opening and recess formed in one end thereof to receive a ferrule secured upon the end of a choker cable; a latch plate slidably mounted within guide grooves formed in the body adjacent the recess opening to detachably engage and secure the ferrule within the body, said plate being movable outwardly from the side of the body to release the ferrule; means for normally moving the latch plate to ferrule securing position; a shoulder formed adjacent the outer end of the plate and accessible through a notch formed in the body adjacent thereto for moving the plate outwardly to release the ferrule when the cable is taut; and a lip formed upon the body adjacent the notch to form a fulcrum for a tool inserted into engagement with the shoulder to move the latch plate.

In witness whereof, I hereunto set my signature.

GEORGE F. HICKOK.
